UNITED STATES PATENT OFFICE.

BERT R. SPAULDING, OF BUFFALO, NEW YORK, ASSIGNOR OF ONE-HALF TO STEPHEN E. SPAULDING, OF SPRINGVILLE, NEW YORK.

BIT-BRACE WRENCH.

No. 897,857.

Specification of Letters Patent.

Patented Sept. 1, 1908.

Application filed October 3, 1907. Serial No. 395,729.

To all whom it may concern:

Be it known that I, BERT R. SPAULDING, a citizen of the United States, residing at Buffalo, in the county of Erie and State of New York, have invented a new and useful Improvement in Bit-Brace Wrenches, of which the following is a specification.

This invention relates more particularly to the class of wrenches which are provided 10 with a shank adapted to be inserted in the socket of an ordinary bit-brace and which are used for tightening or loosening nuts and bolts and more especially those of vehicles and machinery of various kinds.

15 The object of my invention is the construction of a simple and convenient wrench of this type which can be cheaply manufactured.

In the accompanying drawings: Figure 1 is a side elevation of the wrench attached to a 20 bit-brace. Fig. 2 is a sectional elevation of the wrench, on an enlarged scale. Fig. 3 is an end view thereof. Fig. 4 is a transverse section in line 4—4, Fig. 2.

Similar letters of reference indicate corresponding parts throughout the several views.

A indicates the socket of a bit-brace of any ordinary construction, and B the shank of the improved wrench adapted to be inserted and clamped therein like a bit. This shank 30 extends rearwardly from the central portion of a cross head or bar C to the ends of which are secured a pair of parallel forwardly-extending lugs or standards D. In the preferred construction shown in the drawings, 35 the standards and the cross head are united by a tongue-and-mortise joint and transverse rivets e.

F, F indicate a pair of parallel clamping jaws arranged between the standards D and 40 slidable toward and from each other. These jaws extend forwardly some distance beyond the standards to enable them to enter a recess in which an ordinary wrench cannot be conveniently inserted. In their shanks or 45 inner portions the jaws are provided with openings g through which the cross head C passes, thus guiding the jaws on said head.

H indicates a rotary screw journaled at its 50 ends in sockets i formed in the opposing inner faces of the standards D and held against endwise movement therein. This screw is provided centrally with a knurled collar h for turning it and on opposite sides thereof with

right and left hand threads h¹, h² which engage with correspondingly screw-threaded 55 openings j¹, j² in the respective jaws F.

In the use of the wrench, upon turning the operating screw in one or the other direction the sliding jaws are simultaneously adjusted toward or from each other in an obvious 60 manner.

By the relative arrangement of the cross head, the jaws and the adjusting screw herein shown, the jaws always maintain their parallelism and are not liable to bind, and 65 a very strong construction is at the same time obtained.

In assembling the parts, the jaws are passed over opposite ends of the cross-head and engaged with the ends of the right and left hand 70 screw and the socketed standards D are then engaged with the ends of the screw and secured to the cross head.

I claim as my invention:—

1. In a wrench, the combination of a cross 75 head, a pair of spaced standards projecting forwardly from said cross head, a pair of sliding jaws arranged between said standards and having their rear portions constructed to surround said cross head, where- 80 by both the front and rear faces of the cross head form guides for the jaws, and a rotary right and left screw arranged on the front side of said cross head, held against endwise movement in said standards and engaging 85 correspondingly threaded openings in the jaws, substantially as set forth.

2. In a wrench, the combination of a cross head, a pair of spaced standards projecting forwardly from said cross head, a pair of 90 sliding jaws arranged between said standards and having their rear portions constructed to surround said cross head, and a rotary right and left screw arranged on the front side of said cross head, held against endwise move- 95 ment in said standards and engaging said jaws, the jaws being disconnected on the front side of said screw, leaving the space between them unobstructed from their front ends to the screw, substantially as set forth. 100

Witness my hand this 1st day of October, 1907.

BERT R. SPAULDING.
